UNITED STATES PATENT OFFICE.

HERBERT W. COLLINS, OF GRAND FORKS, BRITISH COLUMBIA, CANADA.

HAT-FASTENER.

1,238,639.

Specification of Letters Patent. Patented Aug. 28, 1917.

Application filed April 7, 1914. Serial No. 830,315.

To all whom it may concern:

Be it known that I, HERBERT W. COLLINS, a citizen of Canada, residing at Grand Forks, in the Province of British Columbia and Dominion of Canada, have invented new and useful Improvements in Hat-Fasteners, of which the following is a specification.

An object of the invention is to provide 10 a simple and effective device for fastening hats to the head of the wearer which obviates the necessity of employing the usual hat pins, the invention being adapted for use with all kinds and designs of hats and 15 adapted to present a neat and effective appearance when in use.

The invention contemplates, among other features, the provision of a simple devise which can be placed upon the hat at the time 20 of manufacture or when the hat is purchased and which contemplates a means for engagement with the hair and with the hat whereby the hat will be held upon the head without the use of the usual hat pin which, 25 when passed through a hat, in time tend to mutilate the same in that the hat when the usual hat pins are for a time used therewith will have its sides punctured or perforated and thus present an unsightly appearance, while at the same time it will greatly 30 decrease the wearing quality of the hat.

The invention further contemplates a device which can be applied to all kinds and designs of hats and which can be either arranged 35 upon the hat at the time of manufacturing the same or when the hat is purchased so that, particularly in the latter instance, the purchaser can designate what parts of the hat she desires the device arranged 40 on.

In the further disclosure of the invention reference is to be had to the accompanying drawings, constituting a part of this specification, in which similar characters of reference denote corresponding parts in all the 45 views, and in which:

Figure 1 is a perspective view of the hat showing the device applied thereto;

Fig. 2 is a horizontal sectional view taken 50 through the crown of the hat showing the arrangement of the parts;

Fig. 3 is a perspective view of the bar or pin;

Fig. 4 is a perspective view of the plate or 55 band having the socket thereon;

Fig. 5 is a plan view of a hat, showing a

modified form of my device used in connection therewith;

Fig. 6 is a horizontal sectional view showing the hat shown in Fig. 5 to disclose the 60 arrangement of the device; and

Fig. 7 is a perspective view of the pin and ornamental socket used in the modified form of my device, the same being shown in detached relation.

65

Referring more particularly to the views, I disclose a hat 10 consisting of a crown 11 and brim 12, the crown 11 adjacent the point of formation of the brim 12 therewith on one side of the crown having suitably secured 70 thereto a plurality of eyelets 13, these eyelets being passed through the crown and pressed into the material thereof so as to provide opening to the interior of the crown. In the opposed relation to the eyelets a plurality 75 of plates 14 are secured within the crown, said plates being formed to provide clasps or sockets 15 and pins 16, each consisting of a shank 17 terminating at one end in a knob or ornamental design 18 and at the other 80 end in a pointed head 19, and adapted to be passed through the eyelets 13 and thence through the hair which lies within the crown so that the free ends or the ends of the pins having the heads 19 thereon can be moved 85 into the clasps 15 on the plates 14, said clasps or sockets 15 being tubular and of a spring-like nature, similar to the clasp on a glove so that when the heads 19 are pressed into engagement with the clasps, and which 90 are in the nature of sockets, both ends of the pins will be held securely on the crown 11, with the medial portion of the pins passing through the hair to secure the hat upon the head of the wearer. With this construction, it will be apparent that only one 95 end of the pins, namely, the ornamental or knob ends, will be exposed exteriorly of the crown, the other ends of the pins being arranged within the clasps carried by the 100 plate secured to the inner face of the crown.

Each of the eyelets 13 is diametrically opposite and in horizontal alinement with the central point of the corresponding plate 14 and the tubular sockets on each plate converge toward their eyelet so that the pin 16 which extends loosely through the eyelet may be moved into longitudinal alinement with anyone of the sockets to project its head 19 squarely into engagement therewith. 105 It is important that the center lines of the sockets be in radial alinement with their eye- 110

lets 13 for otherwise the head of the pin would not squarely engage with all of the sockets and unless thus engaged it will be liable to become detached therefrom.

5 I preferably show two pins used in connection with the hat, but it will be understood that one, two or more pins can be employed if necessary.

In the modified form of the device, I provide eyelets 20 on one side of the crown 11 and in opposed relation thereto similar pairs of eyelets 21, with pins 22 adapted to pass through the eyelets 20 and 21 so that the medial portions of the pins will pass through 10 the hair and both ends of the pins will project exteriorly of the crown, one end of each pin 22 having a knob 23 with a somewhat ornamental design thereon, and the other end of each pin terminating in a head 24 15 similar to the head 19, but which head 24 projects exteriorly of the crown and is adapted to receive a socket or knob 25 in the configuration of an ornamental design. As in the preferred form of my device, I 20 preferably show two similar pins in connection with the hat, but it will be understood that either one, two or more pins can be used. With the latter construction both ends of the pins project exteriorly of the 25 crown and both ends have suitable ornamental designs or knobs thereon so that the hat will present a neat and effective appearance when applied to the head of the wearer.

With these constructions it will be apparent that the usual hat pins are dispensed with, thus preventing the formation of an unusual number of perforations in the crown of the hat and which occurs when the usual 30

hat pins are repeatedly used with a hat, it being well known that they cannot be very 40 well arranged to pass through the same apertures made in the hat by the hat pins when they were initially or for the first time used in connection with the hat. Thus there is provided an efficient means for holding the 45 hat upon the head and which will present a neat and effective appearance, while at the same time the wear of the hat will be increased owing to the fact that the same will not be repeatedly perforated and the crown 50 weakened by such perforations.

Having thus described my invention, I claim:

In combination with a hat, a fastener comprising a plate secured to the inner side of 55 the crown of the hat and curved longitudinally to conform to the curvature thereof, a plurality of horizontally aligned sockets formed integrally on the inner side of said plate in spaced relation, an eyelet formed in 60 the hat crown at a point diametrically opposite and in horizontal alinement with the central point of the plate, said sockets being elongated and tubular and converging toward the eyelet, a pin extending loosely 65 through said eyelet and movable into longitudinal alinement with each of said sockets, and a head formed on one extremity of the pin and squarely engageable in each of said 70 sockets.

In testimony whereof I affix my signature in presence of two witnesses.

HERBERT W. COLLINS.
